UNITED STATES PATENT OFFICE.

JAMES P. DOVEL, OF BIRMINGHAM, ALABAMA.

APPARATUS FOR THE PROTECTION OF BLAST-FURNACE JACKETS.

Application filed September 17, 1923. Serial No. 663,283.

My invention relates to new and useful improvements in apparatus for the protection of the jackets or shells of metallurgical blast furnaces and the like, and particularly for 5 the protection of that portion of the shell above the bosh, the lining of which is subjected to the most intense heat and the most rapid deterioration and abrasion.

Heretofore, in this art it has been the practice to incorporate in the refractory brick lining of the furnace above the bosh a number 10 of cast iron coolers connected up with a source of circulating water, and it was the purpose and function of these coolers to protect the surrounding brick work in the lining 15 from temperatures that would melt the same, and thus the theory was that these coolers would greatly increase the life of the lining. In practice, however, experience has shown 20 that when the lining has worn away so as to expose these coolers, either from abrasion, heat, or chemical action, the coolers would invariably burn out and thereupon the furnace man was subjected to expense and 25 trouble of relining his furnace. So far as I am aware, no practical provision has heretofore been made for the removal and replacement of cooling blocks in the brick lining above the mantel, thereby making it possible 30 to repair the furnace.

In the operation of certain blast furnaces under my charge I experienced an abnormally rapid destruction of the lining in a zone 35 extending about 20 feet above the bosh. Throughout a large portion of this zone, which was water cooled, the brick lining was entirely burned away and the shell would have been exposed to the raw stock and the intense heat except for a thin lining of an 40 agglomerate material which formed on the shell and supported the brick lining above it. After an examination of this condition I 45 conceived the idea of building up within the furnace an agglomerate lining composed entirely of slag and stock materials by the introduction through the shell of cooling elements preferably in the form of standard bronze bosh blocks, and by arranging these in such relation that the partially molten metal 50 and fine particles of the stock would agglomerate and build up on and about same until a complete protection or lining having approximately the thickness of the original lining would cover the jacket throughout the 55 zone under treatment, or the whole jacket,

were it desired to provide the original lining by this method.

I also conceived the idea of providing for these cooling blocks a mounting housing or frame, which can be bolted or otherwise attached to the jacket about an opening cut therein to receive the block, and the block, when driven home in the frame, would have a gas tight fit. The advantages of this arrangement permit the ready mounting and 60 removal of the blocks where needed in the furnace without blowing out the furnace, and this arrangement lends itself especially for providing individual mountings for cooling 65 blocks used to repair hot spots. 70

My invention therefore comprises the combination of a bosh block with its mounting frame, as well as the method of utilizing such blocks so as to build up by an agglomeration 75 of stock a protecting lining in the furnace jacket. The lining so built up within the furnace in actual practice has proved more effective than the brick lining and far less subject to deterioration.

The method of practicing my invention and 80 the preferred embodiment of the means to that end will be best understood by reference to the accompanying drawings, which form a part of these specifications, and in which:—

Fig. 1 is a partial elevation and partial 85 section through a furnace equipped with my invention.

Fig. 2 is an enlarged side elevation of a 90 cooling block with its individual mounting frame mounted in the jacket.

Fig. 3 is an end elevation of Fig. 2, showing the block mounted in an individual frame.

Similar reference numerals refer to similar parts throughout the drawings.

In the practice of my invention I propose 95 to protect the jacket of any type of blast furnace above its bosh, by means which will cause the building up of a lining by an agglomeration of materials charged in the furnace, which lining will cover the exposed 100 jacket walls to such an extent and in such manner as to protect them even more effectively than they are at present protected by the brick, and it is within the scope of my invention that the original lining for the furnace may be so created by the utilization of 105 my method and process, as well as that an existing lining may be repaired and replaced in part wherever it has failed.

To illustrate the practice of my invention 110

I have shown in the accompanying drawings a metallurgical blast furnace having a bosh 1, and above this the usual metal jacket or shell 2, which in the drawings is shown as 5 having been previously lined with refractory brick 3. Throughout the zone of maximum abrasion and heat, extending generally about 20 feet above the bosh, I have shown the lining as having disappeared and been replaced 10 by a thin agglomerate lining 4 adhering to the jacket wall. This correctly illustrates the physical condition of a furnace which was treated according to my process as follows. A plurality of bronze bosh blocks 5 of the 15 standard type cored for water circulation were provided and for each block an individual mounting frame 6 was used, this frame having its body portion curved to conform to the curvature of the jacket, and having also 20 a slightly tapered inturned flange 7 surrounding the opening in the frame and adapted to receive the block with a snug, gas tight fit when driven home therein. As shown, the blocks are of sufficient length to extend into 25 the stack almost to the inner limit of the lining. The jacket has an opening 8 cut therein to receive the flange 7. The frame will overlie the jacket about the opening 8 therein sufficiently to receive attaching means to 30 connect it to the jacket. Preferably bolts 9 are used, these being inserted after the frame was mounted in the jacket opening by passing the threaded ends of the bolts outwardly through the jacket and frame and applying 35 nuts to detachably mount the frame with a gas tight joint on the jacket. The cooling blocks are then driven home in their respective frames and when in place are connected up in series by water supply pipes 10, each 40 at one end connected to the inlet nipple 11 at one side of a block and at the other end connected to the outlet nipple 12 of an adjacent block. The blocks as thus mounted in the furnace can be connected up in any suitable 45 manner with each other and with a source of cooling water.

The blocks are to be introduced in the furnace in such relative positions as will produce the results in view. If used to treat a 50 small hot spot, they should be located in such relation thereto that the agglomeration of stock, as indicated at 13 thereon, would gradually fill out the worn or missing portion of the lining at the hot spot. If an entire zone 55 is to be lined or relined the blocks should be arranged at different levels and staggered, the spacings between the blocks being such that they would cause an agglomeration to extend sufficiently to overlap from block to 60 block. In practice I found this to occur satisfactorily where the blocks on a given level were spaced on three foot centers and the lines were spaced about five feet. When 65 so arranged it was found that within a very short time there had agglomerated or built

up on and around the blocks a lining of semi-refractory material composed of particles of ore, ashes, silica, graphite, coke and alumina. The lining thus formed was very hard, and, as cooled by the embedded blocks, was sufficiently refractory to withstand the furnace temperatures. I found by removing a bosh block for inspection that this agglomerate lining extended over its inner end, thus materially protecting it from abrasion at that 70 point, and that the agglomerated lining had built up as well under as over the blocks, it evidently being the case that a gradual accumulation of the semi-molten stock would build up throughout the zone cooled by the 80 blocks until all of the jacket was covered and all of the blocks were entirely embedded in such agglomerate lining.

In a furnace which for 20 feet above its bosh was entirely devoid of brick lining I 85 succeeded, by the placing of cooling blocks in the manner described, in building up an agglomerated replacement lining in a very short time, and from careful inspections and tests of this lining there is no evidence of any deterioration in it at all, apparently there being a gradual replacement of the lining as it is worn by abrasion. This would seem to result from the fact that throughout the entire 90 zone in which the cooling effect of the block is appreciable there will be no diminution of this agglomerated lining. In the event any of the blocks should fail for any reason, it is a very simple and inexpensive matter to unbolt its respective mounting frame, disconnect 100 its pipes 10 and take out the frame and block for inspection, if necessary shutting off the blast temporarily. The block can thus be readily inspected, a new block substituted, and its mounting frame remounted in the 105 jacket. It will be noted that the jacket directly supports the frame and block because the flange 6 will rest on the bottom of the jacket opening 8.

It is one of the most important features 110 of my invention that the frames will permit the blocks to be very readily mounted with a gas tight joint in the furnace while making it simple to remove and replace them. It is important that these cooling blocks be 115 mounted firmly so as to carry the entire weight of lining, as expansion under operating conditions may throw the entire weight of lining on the cooling blocks.

Having thus described my invention, what 120 I claim as new and desire to secure by Letters Patent, is:—

1. A blast furnace having an outer metal jacket, a plurality of artificially cooled projections carried thereby and projecting inwardly therefrom, and an agglomerate lining formed of particles of furnace stock which cohere to and extend about said projections and by reason of the juxtaposition of the latter form a lining for the jacket. 125

2. A blast furnace having an outer metal jacket, a plurality of water cooled blocks mounted to project therethrough approximately to the depth of the furnace lining desired, said blocks being arranged about the portion of the jacket which becomes most highly heated, and an agglomerate lining of stock particles which adheres to and extends about each block, said blocks being so spaced that the lining forming about each will overlap and form a continuous lining for that portion of the jacket which carries the blocks. 65
3. A blast furnace having a bosh, an outer metal jacket above the bosh, and means to protect the lower portion of the jacket comprising a plurality of circumferential rows of internally projecting cooling blocks arranged with the blocks relatively spaced to cause the formation about them of a continuous agglomerate lining covering the interior of the lower portion of the jacket. 70
4. A blast furnace having a bosh, an outer metal jacket above the bosh, and means to protect the lower portion of the jacket comprising a plurality of circumferential rows of internally projecting cooling blocks carried by and outwardly demountable from said jacket and arranged with the blocks of the several rows relatively spaced to cause the formation about them of a continuous agglomerate lining covering the interior of the lower portion of the jacket. 75
5. In a furnace stack, a shell, a lining for the shell formed from agglomerated particles of stock, and water cooled projections embedded in said agglomerate lining. 80
6. A furnace shell having an agglomerate lining of stock particles, and means to vertically support and artificially cool said lining sufficiently to prevent its melting. 85
7. A furnace having a lining of stock particles secured together by semi-fused stock particles, and water cooled projections embedded in said lining and adapted to vertically support the same and prevent its melting. 90
8. The combination with a blast furnace jacket having a cooling block opening therein, of a cooling block frame having a body portion surrounding said opening in the jacket and an inwardly tapering flange extending through the jacket, attaching elements for the body portion of the frame mounted in the jacket and adapted to permit the free outward detachment of the frame from the jacket, and a cooling block mounted with a taper gas tight fit in the flange of the frame and projecting inwardly through said cooling block opening. 95
9. In combination with a blast furnace jacket having a cooling block opening there- 100
- in, of a marginal frame detachably connected to the jacket above said opening and having a flange projecting in line with the jacket opening, and a cooling block inserted through the frame and mounted with a gas tight fit in said frame flange. 105
10. In combination with a blast furnace jacket having a cooling block opening therein, of a marginal frame having an inner marginal flange, said frame being adapted to overlap and reinforce the jacket surrounding said opening, bolts having their threaded ends passing outwardly through the jacket and frame, nuts on said bolts to detachably connect the frame to the jacket with its inner flange in line with a cooling block opening in said jacket, said flange being shaped to conform to the longitudinal and transverse cross-section of a cooling block, a cooling block mounted with a snug gas tight fit in said frame flange, and means to water cool the block. 110
11. The combination of a blast furnace jacket and an agglomerate lining, and a cooling element supported by the jacket and embedded in said lining and disposed to effect self replacement of said lining by chilling and agglomerating stock particles. 115
12. In a blast furnace, a stack, and means for maintaining a lining of substantially uniform thickness in the stack, said means comprising closely spaced cooling elements extending uniformly through the outer wall of the stack and so disposed as to chill and agglomerate refractory components from the stock immediate thereto. 120
13. In a blast furnace, a stack having relatively high and low temperature zones, and means for maintaining an agglomerate lining of substantially uniform thickness in the high temperature zone of the stack, said means comprising closely spaced cooling elements extending uniformly through the outer wall of the stack, said cooling elements being maintained at such a temperature and being so disposed as to chill and agglomerate refractory components in the stock immediate thereto. 125
14. In a blast furnace, a stack embracing a relatively high temperature smelting zone, a metallic jacket for said stack around said zone, an agglomerate lining for the stack at said zone, and a plurality of cooling elements extending through the jacket and interspersed about said zone to chill and agglomerate elements from the descending stock immediate thereto to maintain the agglomerate lining at a uniform thickness. 130

In testimony whereof I, JAMES P. DOVEL, affix my signature.

JAMES P. DOVEL.
